UNITED STATES PATENT OFFICE.

GEORGE WALTHER, OF DAYTON, OHIO, ASSIGNOR TO THE DAYTON STEEL FOUNDRY COMPANY, OF DAYTON, OHIO, A CORPORATION OF OHIO.

WHEEL.

Application filed July 5, 1922. Serial No. 572,832.

To all whom it may concern:

Be it known that I, GEORGE WALTHER, a citizen of the United States, residing at Dayton, in the county of Montgomery and 5 State of Ohio, have invented certain new and useful Improvements in Wheels, of which the following is a specification, reference being had therein to the accompanying drawing.

10 My invention relates to wheels and in particular to the apparatus for cast wheels.

It is the object of my invention to provide a form of a hub core which will eliminate the present difficulty of the hot turbulent 15 metal eating away the green sand adjacent the point of pouring the metal in the hub.

It has been the practice to have green sand adjacent the hub core and spoke cores where the metal was poured. Sometimes 20 the dry sand pouring opening liner was utilized but this was subject to being upset by the turbulent incoming metal.

It is the object of my invention to provide a core portion which will prevent the 25 contact of the incoming metal with the green sand, and will provide a hard dry sand baked member to form the pouring opening, a portion of the exterior walls of the hub and a portion of the inner ends 30 of the spoke cores, all as a unit.

It is also possible as an additional advantage of my invention to provide for the manufacture of such members in quantity and in varying sizes so as to put the 35 production of such cores on a quantity manufacturing basis.

It is also possible to vary the dimensions 40 of the hubs which is the point of greatest variation between standard sizes of wheels in order to accommodate the different productions of different manufacturers of axles and bearings.

Referring to the drawings:

45 Fig. 1 is a section through a flask with a dry sand core and the green sand in place;

Fig. 2 is a plan view of the dry sand pouring member in question.

Referring to the details of the drawings, 50 1 is a bottom board, 2 is the drag portion of the flask and 3 is the cope portion of the flask. These portions of the flask are positioned in respect to one another by their 55 positioning pins 4. The usual green sand 5 is in the drag portion of the flask 2. Placed within the green sand which has been suit-

ably moulded to form the exterior of one half of the wheel, is a depression of angular character designated 6 in which is placed a ring consisting of baked dry sand and designated 7, which forms the exterior of a portion of the spokes and hub. 8 is a hub core located upon the green sand. 9 is the drag portion of the rim and spoke cores having the arbors 10. The upper or cope portion of these cores is designated 11. The inner 65 ends of core 11 designated 12 are formed as a part of the exterior cap end hub member 13 which has a plurality of radiating arms 14 and a pouring mouth 15. The chaplets 16 separate inner core ends 12 from cap 70 13 and position them although 12 and 13 form a continuous structure otherwise. Similar chaplets form a similar function as at 17. The chaplets 17 determine the position of core 9 with respect to ring 7. 75

The member 13 is provided with a series of shoulders 18 upon which the green sand 20 in the cope portion of the flask rests. consequently, the green sand serves to maintain cap 13 in position. Cap 13 is positioned readily by its engagement with core 9 and 11 through 12. It is also positioned by its engagement with the green sand 20. It cannot float upwardly to the green sand 20 being on top of a substantial portion of 85 it. Being of hard dry sand it resists the eroding action of the incoming metal during the pouring of the wheel.

It will be understood that I do not desire to be confined to this specific adaptation of my invention, but comprehend without 90 it suitable modifications which may be necessary in adapting it to varying conditions.

Having thus fully described my invention, what I claim as new and desire to secure by Letters Patent, is:—

1. In a core member, a tubular member with a pouring aperture therein, a stepped portion on the exterior thereof for engagement with green sand, and a cutaway portion on the interior thereof adapted to form the exterior of a hub of a cast wheel. 100

2. In a core member, a tubular member with a pouring aperture therein, a stepped portion on the exterior thereof for engagement with green sand, and a cutaway portion on the interior thereof adapted to form the exterior of a hub of a cast wheel, a portion of said member being adapted to form 110

the inner ends of spoke cores for forming the spokes, and a portion of the hub of said wheels.

3. In a core member, a tubular member 5 with a pouring aperture therein, a stepped portion on the exterior thereof for engagement with green sand, and a cutaway portion on the interior thereof adapted to form the exterior of a hub of a cast wheel, a portion 10 of said member being adapted to form the inner ends of spoke cores for forming the spokes, a portion of the hub of said wheels, and chaplets between the hub portion of this core member and the portions 15 serving as the inner ends of the spoke cores.

4. In a core, a cylindrical member having a plurality of separated arms radiating therefrom, a pouring tubular portion having an aperture therein, and means carried by 20 said arms to serve as portions of the inner ends of spoke cores, and means thereon for engaging therewith the inner ends of cope portions of the spoke cores.

5. In a core, a cylindrical member having 25 a plurality of separated arms radiating therefrom, a pouring tubular portion having an aperture therein, means carried by said arms to serve as portions of the inner ends of spoke cores, means thereon for engaging therewith the inner ends of cope portions of the spoke cores, and means on the 30 exterior thereof for engagement with green sand to prevent the vertical and lateral movement of the member.

6. In combination in a flask with green sand in the drag portion thereof, an angular hub forming member of dry sand located thereon, spoke cores located thereon, a hub core member to form the exterior of the hub, and a portion of the spokes moulded as a unit on the inner ends of the member to form a portion of the inner ends thereof, said portions being in engagement with the drag and cope portions of the spoke cores. 35

7. In combination in a flask with green sand in the drag portion thereof, an angular hub forming member of dry sand located thereon, spoke cores located thereon, a hub core member to form the exterior of the hub, and a portion of the spokes moulded as a unit on the inner ends of the member to form a portion of the inner ends thereof, said portions being in engagement with the drag and cope portions of the spoke cores, 40 said member having a passageway for the introduction of metal to the wheel to be cast and means exterior thereof to prevent the lateral and vertical shifting of said member with which the green sand is in engagement. 45

8. In combination, a flask, a spoke core, a hub core and a hub cap core having a pouring aperture, and means integral therewith forming a portion of the inner ends of the spokes. 50

In testimony whereof, I affix my signature. 55

GEORGE WALTHER.
